(57) **ABSTRACT**

Disclosed is an antenna having a plurality of radiator columns and an integrated phase shifter/calibration board. The radiator columns have radiator clusters that may be differentially phase to provide beam tilt. The input traces of each of the phase shifters is capacitively coupled to a Wilkinson power divider that sums the power of all the input signals.

(Co)

pattern that provides phase alignment for all the output signals to prevent phase mismatches between signals fed to the radiator clusters.

This application is a U.S. National Stage application filed under 35 U.S.C. § 371 of PCT/US2021/051878 filed Sep. 24, 2021, which claims the benefit of priority to U. S. Provisional Application No. 63/084,889 filed Sep. 29, 2020, each of which is hereby incorporated herein by reference in its entirety.

BACKGROUND OF THE DISCLOSURE

Field of the Invention

The present invention relates to wireless communications, and more particularly to cellular antennas that provide beam forming and MIMO (Multi Input-Multi Output) in higher frequency bands.

Related Art

The advent of new high frequency bands for use in cellular communications brings both opportunities and technical challenges. In addition to the traditional low band (LB) and mid band (MB) frequency regimes (617-894 MHz and 1695-2690 MHz, respectively), the introduction of C-Band and CBRS (Citizens Broadband Radio Service) provides additional spectrum of 3.4-4.2 GHz. The smaller sizes of individual radiators (corresponding to higher frequencies) of CBRS and the C-Band enables the construction of array faces within traditional cellular macro antennas that facilitate features such as 4x4 MIMO (Multiple Input Multiple Output) and 8T8R (8-port Transmit, 8-port Receive) with beamforming.

A challenge arises in implementing 8T8R beamforming and 4x4 MIMO within an antenna in that the performance of these features depends greatly on phase coherence between the signals on the ports. Any phase mismatch can seriously degrade the performance of the antenna. For example, a phase mismatch is introduced to one of the port signals can impart an insertion loss to the signals provided to the antenna radiators. This not only decreases the efficiency of the antenna but also degrades the quality of the gain pattern intended by the beamforming weights applied to the different columns of radiators. This challenge becomes exacerbated with higher frequencies in that minor phase mismatches due to cable length differences within the antenna. For example, in the C-Band, a 1 mm difference in cable length can impart a 10 degree phase mismatch between signals. Further, these phase errors due to cable length mismatches are cumulative with each set of cables introduced into the signal paths. Given that the precision of typical cable cutting machines is around +/-0.5 mm, these errors can compound. Further, for conventional antennas, the cables for each given port may be of different length, which not only complicates the manufacturing process and increases manufacturing costs, but also introduces more risk in phase mismatches from improper cable allocation that can lead to lack of performance consistencies.

Accordingly, what is needed is an integrated antenna calibration and phase shifter board that compensates for phase differences, that reduces the number of cables required in the signal path of each signal port, and simplifies manufacturing by enabling cables of identical length across multiple ports' signal paths.

SUMMARY OF THE DISCLOSURE

An aspect of the present disclosure involves an antenna. The antenna comprises a plurality of radiator columns, each 5 radiator column having a plurality of radiator clusters; a phase shifter/calibration board having a plurality input ports and a plurality of phase shifters, each of the plurality of phase shifters is coupled to a corresponding input port via an input trace, each input trace is capacitively coupled to provide a representative power signal to one of a plurality of power dividers, wherein each phase shifter has a plurality of phase shifter output traces having an output port, each of the output ports is coupled to a corresponding radiator cluster of 10 a corresponding radiator column, wherein a subset of the plurality of phase shifter output traces have a designated meander pattern that collectively provides phase matching between the output ports, wherein the plurality of power dividers sums the plurality of representative power signals 15 into a single calibration signal; and a plurality of RF cables, each of the plurality of RF cables couples a given phase shifter output port to its corresponding radiator cluster of its corresponding radiator column, wherein the plurality of RF cables have the same length.

BRIEF DESCRIPTION OF THE DRAWINGS

FIG. 1 illustrates an exemplary 8T8R array face coupled to an integrated phase compensated calibration board according to the disclosure.

FIG. 2 illustrates an exemplary integrated phase shifter/calibration board according to the disclosure.

FIG. 3A illustrates an exemplary integrated phase shifter/calibration signal path according to the disclosure.

FIG. 3B is another illustration of the exemplary integrated phase shifter/calibration signal path of FIG. 3A, providing example dimensions for the coupling point between in input trace and a calibration trace.

FIG. 3C is another illustration of the exemplary integrated phase shifter/calibration signal path of FIG. 3A, providing example dimensions for exemplary traces and meander turns according to the disclosure.

**DESCRIPTION OF EXEMPLARY
EMBODIMENTS**

FIG. 1 illustrates an exemplary array assembly according to the disclosure. Array face assembly 100 includes a plurality of radiator columns 105w, 105x, 105y, and 105z, each having a plurality of crossed radiator pairs 102, and an integrated phase compensated calibration board 135 (hereinafter phase/calibration board 135). In this example, radiator column 105w has ten radiator pairs 102, each radiator pair 102 having a dipole 110a of a first polarization and a crossed dipole 110b of a second polarization that is orthogonal to the first polarization; similarly, radiator column 105x has ten radiator pairs 102, each radiator pair 102 having a dipole 110c of the first polarization and a crossed dipole 110d of the second polarization; radiator column 105y has ten radiator pairs 102, each radiator pair 102 having a dipole 110e of the first polarization and a crossed dipole 110f of the second polarization; and radiator column 105z also has ten radiator pairs 102, each radiator pair 102 having a dipole 110g of the first polarization and a crossed dipole 110h of the second polarization. In this example, the arrangement of radiator columns 105w-z, each having two sets of orthogonally polarized radiators 110 is consistent with an 8T8R

array face. However, it will be understood that other array face configurations are possible and within the scope of the disclosure.

In this example, each radiator column **105w-z** has ten crossed radiator pairs **102** that are divided into five clusters of two radiator pairs. Each cluster of two radiator pairs **102** has two signal feeds, one per polarization. Each cluster of two radiator pairs **102** may have, for each polarization, a signal splitter (not shown) that splits the RF signal from each of the two signal feeds to two balun circuits (not shown) for each polarization. Each balun circuit is disposed on a balun stem (not shown) that supports the dipoles **110** of the corresponding radiator pair **102**. The signal feeds to each cluster of two radiator pairs **102** are coupled to outputs of phase shifters, as described below.

Phase/calibration board **135** has a plurality of phase shifters PS1-PS8, each of which correspond to a single set of dipoles **110a-h** corresponding to a given polarization within a given radiator column **105w-z**. For example, phase shifter PS1 has a signal input port **120a**. Phase shifter PS1 may further have five output signal feeds: feed **115a** that corresponds to the reference port (no phase shift imparted by phase shifter PS1) to the dipoles **110a** of the center cluster of two radiator pairs **102** within radiator column **105w**; feed **116a** that corresponds to a first output of phase shifter PS1 that imparts a first phase shift to the signal from input port **120a** that gets fed to the dipoles **110a** of the cluster of two radiator pairs **102** distal and adjacent to the center cluster; feed **117a** that corresponds to a second output of phase shifter PS1 that imparts a second phase shift to the signal from input port **120a** that gets fed to the dipoles **110a** of the cluster of two radiator pairs **102** at the distal end of radiator column **105w**; feed **118a** that corresponds to a third output of phase shifter PS1 that imparts a third phase shift to the signal from input port **120a** that gets fed to the dipoles **110a** of the cluster of two radiator pairs **102** proximal and adjacent to the center cluster; and feed **119a** that corresponds to a fourth output of phase shifter PS1 that imparts a fourth phase shift to the signal from input port **120a** that gets fed to the dipoles **110a** of the cluster of two radiator pairs **102** at the proximal end of radiator column **105w**.

Similarly, phase shifter PS2 has a signal input port **120b** and five signal feeds **115b-119b**, which provide signals to the dipoles **110b** of the corresponding clusters of radiator pairs according to a signal connection similar to that of phase shifter **120a** but for the orthogonal polarization within the same radiator column **105w**. It will be understood that signal input ports **120a** and **120b** may correspond to distinct and independent signals. It will also be understood that the connections of signal feeds **115b-119b**, with their corresponding phases imparted by corresponding phase shifter PS2, may be similar as described above with respect to phase shifter PS1 and dipoles **110a**.

Phase shifters PS3 and PS4 may be coupled to respective dipoles **110c** and **110d** of radiator column **105x** in a manner similar to that described with respect to phase shifters PS1 and PS2 and radiator column **105w**; phase shifters PS5 and PS6 may be coupled to respective dipoles **110e** and **110f** of radiator column **105y** in a manner similar to that described with respect to phase shifters PS1 and PS2 and radiator column **105w**; and phase shifters PS7 and PS8 may be coupled to respective dipoles **110g** and **110h** of radiator column **105z** in a similar corresponding manner.

Having different clusters of dipoles **110a-h** within a given radiator column **105w-z** fed with signals such that each cluster's signal has a different phase shift imparted by corresponding phase shifter PS1-8 enables independent

beam pointing of each signal input **120a-h** along an axis parallel to the axis of radiator columns **105w-z** according to conventional Remote Electrical Tilt methods.

Each of the phase shifters PS1-8 are coupled to the calibration segment **130** of phase/calibration board **135**. Calibration segment **130**, in addition to being coupled to each of the input signal ports **120a-h**, provides a calibration output port **140** and a Bias-T port **145**, which are described in further detail below.

FIG. 2 illustrates an exemplary phase/calibration board **135** according to the disclosure. Phase/calibration board **135** has input signal ports **120a-h**, each of which has an input trace **215a-h** that couples to its corresponding reference port **115a-h** (coupled to corresponding reference feed **115a-h**) via the base of a corresponding phase shifter wiper arm **207**. The input trace **215a-h** coupled to corresponding signal ports **120a-h** also couples to a Wilkinson power divider **210** at coupling point **220a-h**. A Wilkinson power divider is an example of a power divider that might be used. Other power divider circuits may be used provided that they each tap into the signal at a given input trace **215a-h** with minimal power loss and sum the powers of the tapped signals into a single signal. Examples include a two-way splitter without resistors, and a rat-race coupler, although these will not have the efficiency of a Wilkinson power divider.

Accordingly, each coupling point **220a-h** provides the Wilkinson power divider **210** a copy of the signal present at input traces **215a-h** with a 26 dB drop. In doing so, each signal at the input signal ports **120a-h** are tapped (uniformly attenuated by 26 dB) in such a way that minimal signal power is extracted from the signals to be fed to radiator columns **105w-z**. As illustrated, each successive Wilkinson power divider **210** sums the detected signal power tapped from input traces **215a-h**, and the arrangement of cascaded Wilkinson power dividers **210** sums the power of tapped signals from input traces **215a-h** according to the following combination: $((215a+215b)+(215c+215d)+((215e+215f)+(215g+215h)))$. The output of the apex Wilkinson Power Divider **210**, which is coupled to calibration output port **140**, is the summed signal power according to this relation.

In keeping with Wilkinson power divider theory, the signal of calibration trace **309** corresponding to input trace **215a** (for example) is summed with the signal of calibration trace **309** corresponding to input trace **215b**. Both calibration traces **309** are input to corresponding Wilkinson power divider **210** with a loss of -3 dB (half power) at each input port. Accordingly, given that the two signals are summed at the output of the Wilkinson power divider **210**, the half-power losses at the input ports are restored by the summing of the two signals into a single output. This lossless operation, however, depends on the two signals at calibration traces **309** (and thus at input traces **215a** and **215b**) are equal in magnitude and phase. The lossless nature of operation of the Wilkinson power divider **210** applies for each level of their cascading topology. Accordingly, signal at calibration port **140** is a lossless combination of a 26 dB dropped representation of the signals at input traces **215a-h** (and thus input ports **120a-h**), assuming that all of the signals at input ports **120a-h** are of equal magnitude and phase. However, if one or more of the signals at input ports **120a-h** experiences a phase mismatch to the others, the cascaded Wilkinson power dividers in the summation path of the cascade topology are no longer lossless, and the signal level at calibration output port **140** will drop. Accordingly, a signal drop beyond 2 dB below the expected 26 dB drop may indicate a phase mismatch at one or more input port **120a-h**.

Any phase mismatch between the signals at input ports **120a-h** will result in a beamforming error. For example, a phase mismatch might be due to an RF cable carrying one of the input signals **120a-h** being replaced by one having a different length. Regardless of how imparted, a phase mismatch leads to an increase in insertion loss at the relevant input trace **215a-h**, which in turn leads to a drop in power at calibration output port **140**. Another example might be the failure of one of the phase shifters **PS1-8**. This also would result in a drop in signal at the corresponding input trace **215a-h**, which would in turn lead to a reduction of signal power at calibration output port **140**.

A network operator or neutral host may deploy equipment that monitors signal power at calibration output port **140**. If the signal power at calibration output port **140** drops below a predetermined threshold (indicating a phase mismatch or malfunction in the RF path of one of the input signals **120a-h**) the operator or neutral host may either increase the power at a suspect mismatched input signal **120a-h** or change the phase of a suspect mismatched input signal **120a-h**. Either actions compensates for insertion loss.

Phase/calibration board **135** further includes a Bias-T circuit **225** with Bias-T output port **145**. Bias-T circuit **225** filters out the sinusoidal components of the signal present at calibration output port **140** to provide a DC voltage output at Bias-T output port **145**. This DC voltage may be used by components within the antenna in which array face **100** is integrated. For example, the DC voltage from Bias-T output port **145** may be used to power the Remote Electrical Tilt (RET) motors that drive the phase shifter wiper arms **207**.

FIG. 3A illustrates an exemplary integrated phase shifter/calibration signal path **300** according to the disclosure. Phase shifter/calibration signal path **300** may be one of the eight signal paths illustrated in FIG. 2. Phase shifter/calibration signal path **300** has a signal input **120** and an output reference port **115** that corresponds to a central radiator pair cluster on a corresponding radiator column **105**; a proximal end radiator cluster signal output **119** that corresponds to the “bottom” radiator pair cluster on the corresponding radiator column **105**; a proximal inner radiator cluster signal output **118** that corresponds to the “lower” radiator pair cluster that is adjacent to the central radiator pair cluster; a distal end radiator signal output **117** that corresponds to the “upper” end radiator pair cluster on the corresponding radiator column **105**; and a distal inner radiator cluster signal output **116** that corresponds to the “upper” radiator pair cluster that is adjacent to the central radiator pair cluster on the corresponding radiator column **105**.

FIG. 3B is a closer view of coupling point **220** of phase shifter/calibration signal path **300**, providing exemplary dimensions. As illustrated, contiguous to signal input **120** is input trace **215**, which capacitively couples to calibration trace **309** at coupling point **220**. Input trace **215** couples to output reference port **115** via reference port trace **315**, which is coupled to the phase shifter base conductor **307**. The extent of the coupling at coupling point **220**, which is tailored to couple with a 26 dB drop for the signal on calibration trace **309**, may be controlled by the length over which calibration trace **309** is adjacent to input trace **215**, and their proximity, at coupling point **220**. In the example provided, the length over which calibration trace **309** is adjacent to input trace **215** may be 14 mm, and the two traces may be spaced apart at 0.54 mm. Calibration trace **309** is part of Wilkinson power divider **210**, which includes a dissipating resistor **345**, which provides cancelation of minor phase mismatches.

In addition to reference port trace **315**, phase shifter/calibration signal path **300** has four output traces, each corresponding to signal outputs **116/117/118/119**. For example, proximal end radiator cluster signal output **119** is coupled to output trace **319**; and distal end radiator signal output **117** is coupled to output trace **317**. Although output traces **319** and **317** may be formed of a single contiguous conductive trace, output trace **319** may be defined as beginning at the capacitive couple at phase shifter wiper arm **207** and extending in one direction; and output trace **317** may also be defined as beginning at the capacitive couple at phase shifter wiper arm **207** and extending in the opposite direction. Similarly, proximal inner radiator cluster signal output **118** is coupled to output trace **318**; and distal inner radiator cluster signal output **116** is coupled to output trace **316**. Further, although output traces **318** and **316** may be formed of a single contiguous conductive trace, output trace **318** may be defined as beginning at the capacitive couple at phase shifter wiper arm **207** and extending in one direction; and output trace **316** may also be defined as beginning at the capacitive couple at phase shifter wiper arm **207** and extending in the opposite direction.

Each output trace **315/316/317/318/319** may have a respective designated meander pattern that provides individual phase deltas. The individual phase deltas provide phase matching between signal outputs **115/116/117/118/119** to compensate for individual systemic phase mismatches. This enables the internal RF cables (not shown) between the phase shifters **PS1-8** and radiator columns **105w-z** to be formed of a single length, greatly simplifying the manufacture of the antenna. However, complications arise in providing meander patterns for output traces **315/316/317/318/319** due to possible coupling between meander features of a single output trace, as well as cross coupling between adjacent output traces.

For each output trace **315/316/317/318/319**, phase matching control that minimizes internal coupling as well as cross coupling may involve tailored use of the following trace design features: number of meander turns **335**; spacing of meander turns **322**; width of meander turns **324**, staggering of meander turns **335** for adjacent output traces; and length of chamfer **330**. In the example illustrated in FIG. 3A, reference port trace **315** has six meander turns **335** between phase shifter base conductor **307** and signal output **115**; output trace **316** has three meander turns **335**; output trace **317** might not have a meander turn, which may be expected, given that the distal end radiator signal output **117** corresponds to the “upper” end radiator pair cluster on the corresponding radiator column **105** and is likely the furthest in distance from phase shifter/calibration signal path **300**; output trace **318** has four meander turns **335**; and output trace **319** has two meander turns **335**.

The spacing of meander turns **322** should be sufficiently long to prevent coupling between parallel segments of the given individual output trace **315/316/317/318/319**. If more phase delay is required, the width of meander turn **324** can be increased, but this may place the given output trace in sufficient proximity to an adjacent output trace to cause cross coupling. To mitigate this, the meander turns **335** of adjacent output traces may be staggered to reduce proximity. To further reduce the risk of cross coupling, chamfers **330** may be added at the corners of meander turns **335** to help maintain distance between adjacent output traces.

FIG. 3C provides example dimensions for the output traces **315/316/317/318/319**, the widths of their meander turn spacings **322**, and their respective meander turn spacings **324**.

Each of the output traces **315/316/317/318/319** may be formed of 1.4 mil Copper on a printed circuit board. Given that trace etching precision may be +/-3 mil, this offers considerable precision in adjusting the differential phases of each output trace to mitigate phase mismatch, relative to the +/-0.5 mm precision in RF cable length. With the systemic phase mismatches compensated as described herein, each of the RF cables (not shown) between signal outputs **115/116/117/118/119** and their respective radiator pair clusters may be of the same length. This may significantly reduce the complexity and cost of manufacture of the antenna in which exemplary array face **100** is deployed while mitigating phase mismatches that lead to beamforming errors.

Accordingly, an antenna with exemplary array face **100** provides the following capabilities and advantages. First, phase alignment is critical in 8T8R scenarios in which all radiator columns are used to form a broadcast beam (one per polarization) that can be tilted, to form a service beam that can be scanned as well as tilted. It enables an operator to identify failure of one or more phase shifters as well as to identify and compensate for externally-induced phase mismatch (change in cable with one of a different length). Additionally, uniformity in phase is built into the antenna by the combination of higher integration and phase alignment via designated meander patterns, eliminating the need for certain cables between the phase shifter and the calibration board as well as enabling the use of RF cables of a single length to couple the phase shifters to the corresponding radiator clusters, thereby reducing cost as well as eliminating another source of potential detrimental phase deltas.

What is claimed is:

1. An antenna, comprising:
  - a plurality of radiator columns, each radiator column having a plurality of radiator clusters;
  - a phase shifter/calibration board having a plurality of input ports and a plurality of phase shifters, each of the plurality of phase shifters is coupled to a corresponding input port via an input trace, each input trace is capacitively coupled to provide a representative power signal to one of a plurality of power dividers, wherein each phase shifter has a plurality of phase shifter output traces having an output port, each of the output ports is coupled to a corresponding radiator cluster of a corresponding radiator column, wherein a subset of the plurality of phase shifter output traces have a designated meander pattern that collectively provides phase matching between the output ports, wherein a first designated meander pattern is adjacent to a second

designated meander pattern, wherein the first designated meander pattern and the second designated meander pattern include at least two turns of **90** degrees, and wherein meander turns of the first designated meander pattern are staggered relative to meander turns of the second designated meander pattern, wherein the plurality of power dividers sums the plurality of representative power signals into a single calibration signal; and a plurality of RF cables, each of the plurality of RF cables couples a given phase shifter output port to its corresponding radiator cluster of its corresponding radiator column, wherein the plurality of RF cables have the same length.

2. The antenna of claim 1, wherein each of the plurality of radiator columns comprises a plurality of crossed dipoles, wherein each of the crossed dipoles has a first dipole at a first polarization orientation and a second dipole at a second polarization orientation, wherein the first dipole is coupled to a first phase shifter and the second dipole is coupled to a second phase shifter.

3. The antenna of claim 2, wherein each of the radiator clusters comprises two sets of crossed dipoles.

4. The antenna of claim 3, wherein each radiator column comprises five radiator clusters, each phase shifter comprises five output ports, and the subset of the plurality of phase shifter output traces comprises four phase shifter output traces.

5. The antenna of claim 1, wherein the plurality of power dividers comprises a plurality of Wilkinson power dividers.

6. The antenna of claim 1, wherein each subset of the plurality of phase shifter output traces comprises a distinct designated meander pattern.

7. The antenna of claim 6, wherein each distinct designated meander pattern comprises one or more meander turns, each meander turn having a meander turn width and a meander turn spacing, wherein the meander turn width and meander turn spacing mitigate coupling within the corresponding phase shifter output trace.

8. The antenna of claim 7, wherein the designated meander patterns of adjacent phase shifter output traces within the subset of phase shifter output traces comprise staggered meander turns to mitigate cross coupling between the corresponding phase shifter output traces.

9. The antenna of claim 8, wherein the designated meander patterns of adjacent phase shifter output traces within the subset of phase shifter output traces comprise one or more chamfers.
